UNITED STATES PATENT OFFICE.

CHARLES A. BUTLER, OF OKMULGEE, OKLAHOMA.

CASING CLAMP.

Application filed March 15, 1928. Serial No. 262,011.

This invention relates to improvements in casing clamps, and more particularly concerns a construction of such devices whereby they may be made light and strong.

5 In well drilling work, a casing clamp is an instrument to be located around a length of casing, usually just beneath a coupling, to hold the casing in a given position with respect to the ground, or to assist in raising and lowering it. Heretofore, casing clamps have been made of two parts, each formed of 10 boiler plate or similar strong sheet metal bent to provide a semi-circular trough intermediate its length and with plane ends. Two such clamps were placed around the casing and the plane ends were bolted together. The 15 casing coupling rested upon the upper edge of each of the plates, and it was found that with a heavy weight or casing—for example with 20 many hundred feet of casing in an oil well—the weight upon the clamp would cause it to buckle or pinch, the trough-like central portion tending to move into the well while the plane ends bent upward so that the upper 25 edges of the trough adjacent the plane ends were pinched in beneath the coupling, resulting in a crushing of the casing at this point, and the establishing of a leak or leaks between the casing and its connection; sometimes 30 the coupling connection was forced off from the casing, and the latter would drop into the well, thus not only losing the length of casing, but ruining the well.

According to the present invention, a casing 35 clamp is provided which may be employed either for holding a casing at a predetermined height in the well, or for even raising the casing out of the well or lowering it into the well. By virtue of the construction employed, the casing may be made very strong 40 for a very light weight: and by reason of the possible shape, access is afforded to the casing immediately at the clamp and/or to its coupling connection.

45 In the drawings:

Figure 1 is a side elevation of the casing clamp, with a length of casing indicated in dotted lines therein;

Fig. 2 is a plan view of the casing clamp 50 assembled;

Fig. 3 is a perspective view of one section of the clamp.

As shown in these drawings, the assembled 55 casing clamp is composed of two parts A, B, which may be identical in shape, which are

assembled together by means of connecting bolts or other connecting means.

Each of these sections has an abutment wall 60 formed in two parts 10, 10, which are spaced apart by a distance somewhat greater than the diameter of the casing with which the clamp is to be employed. These two sections of the abutment walls are connected by a semi-circular wall 11 providing a semi-circular trough to receive its half of the casing. 65 A web 12 is shown parallel to the abutment wall 10 in the illustration. The several walls 10, 11, 12 are connected together by a floor 13 which in the illustrated form is shown as forming the bottom surface of the clamp so 70 that it may rest directly upon beams or other members about the mouth of the well.

The ends of the abutment wall 10 are cut away to form a bevelled surface 14 at an acute angle to the floor 13: and the ends of the web 12 are similarly cut away each by an inclined surface 15. It will be noted that the surface 14 extends above the surface 15 in the side elevation of Fig. 1, to afford an easy and ready access to the connecting bolts 16 75 which hold the two clamp members together adjacent the upper surface. The abutment wall 10 is provided with suitable holes for the bolts, and also for the further bolts 18 located near the floor 13. These latter bolts 18 are 80 preferably made stronger than the bolts 16 and pass through both the abutment walls 10 and the stiffening or web walls 12. The nuts 17 are employed to hold these bolts 18 in position and to assist in clamping the members 85 together adjacent the floors 13.

In order to employ the device for gripping a casing, the two sections A and B are placed together as shown in Fig. 2, around the casing and beneath the coupling connection at 90 the upper end of the particular section of casing. The two members A and B are then bolted together by the bolts 16 and 18, and the casing lowered until its coupling rests firmly on the upper edge of the semi-circular walls 100 of the respective members, which have now formed a circular hole slightly larger than the diameter of the casing. The floor 13 may rest upon beams around the mouth of the well to support the length of casing in the ground. 105

If it be desired to use the clamp for raising and lowering casing links, links 20 are placed in position between the abutment walls 10 and the webs 12 during the insertion of the bolts 18, and may be con- 110

nected at their upper ends with any suitable raising and lowering appliance. The bolts 18, being of large diameter and being supported both adjacent their ends and intermediate their ends, are not subject to bending under the upward stress of the links 20 and it will be noted that the spaced relationship of the walls 10 and 12 facilitates a gripping of the casing without crushing: 10 and further that by the particular arrangement of the respective bolts 16 and 18, the links 20 are free to move without interference by the bolt 16 on the one hand, and on the other hand the bolt 16 may be easily 15 placed and removed without interference by the location of the bolt 18 and of the webs 12.

It is obvious that the invention is not limited solely to the form of execution shown as an illustration: but that it may be otherwise employed within the scope of the appended claims.

What is claimed as new is:

1. In a casing clamp, a pair of clamping members and means to hold said members clamped about a casing; each of said members having an abutment wall for engagement with the other member and a casing receiving trough formed in said abutment wall, each of said members also having a floor at a right angle to said abutment wall and a stiffening web at a right angle to said floor and extending away therefrom in the same direction as said abutment wall.
2. In a casing clamp, a pair of clamping members and means to hold said members clamped about a casing; each of said members having an abutment wall for engagement with the other members and a casing receiving trough formed in said abutment wall, each of said members also having a floor at a right angle to said abutment wall, and a stiffening web parallel to said abutment wall, said wall, floor and web being rigidly connected together.
3. In a casing clamp, a pair of clamping members having an abutment wall in two sections in the same plane spaced apart, a semi-circular wall joining said abutment wall sections and providing a semi-circular cas-

ing receiving trough, each of said members also having a floor at a right angle to said abutment wall and a stiffening web parallel to said abutment wall and substantially tangential to the semi-circular wall, said abutment wall and semi-circular wall, said floor and said web being connected rigidly together.

4. In a casing clamp, a pair of clamping members and means to hold said members clamped about a casing; each of said members having an abutment wall for engagement with the other member and a casing receiving trough formed in said abutment wall, each of said members also having a floor at a right angle to said abutment wall, and a stiffening web connected to the wall of said trough and extending away therefrom and from said floor in the same direction as said abutment wall, the ends of said wall and web being inclined at an acute angle with respect to said floor to afford free access to the casing as it projects from said clamp.

5. In a casing clamp, an integrally formed clamping member having an abutment wall in two sections in the same plane and spaced apart, a semi-circular wall joining said abutment wall sections and providing a casing receiving trough, a floor at a right angle to said abutment wall, and a stiffening web parallel to said abutment wall and merging with said semi-circular wall.

6. In a casing clamp, a pair of clamping members and means to hold said members clamped about a casing, each of said members having an abutment wall for engagement with the other member and a casing receiving trough formed in said abutment wall, each of said members also having a floor at a right angle to said abutment wall and a stiffening web joined to said floor and spaced from said abutment wall, bolts passing through said webs and wall, and lifting links engaging said bolts intermediate said webs and walls.

In testimony whereof, I affix my signature.

CHARLES A. BUTLER.
